UNITED STATES PATENT OFFICE.

ROBERT A. NEILSON AND ARTHUR H. WATSON, OF CHICAGO, ILLINOIS; SAID WATSON
ASSIGNOR TO SAID NEILSON.

SELF-ADJUSTING COLLAR BUTTON.

Application filed January 21, 1927. Serial No. 162,444.

Our invention relates to improvements in self-adjusting collar buttons, particularly to that type of button in which means are provided for tightly compressing the superimposed flaps of the collar and collar band at the buttonhole.

An object of our invention is to provide a collar button of the character described which is inserted through the buttonholes 10 of the collar band and collar in precisely the same manner as the ordinary type of rigid collar button and which incorporates automatic means for drawing the head toward the rear plate of the button so as to 15 yieldingly compress the superimposed portions of the band and collar.

A further object of our invention is to provide a collar button of the character described, in which the rear face plate of 20 the button is constantly held into close engagement with the adjacent surface of the collar band so as to obviate the possibility of irritation to the neck of the wearer as by unnecessary protrusion of this portion 25 of the button from the collar band.

A further object of the invention is to provide a collar button of the character described, in which, particularly, novel means is employed for obtaining the yielding 30 retraction of the head so as to minimize the space occupied by such means.

Other objects and advantages of our invention will appear more fully from the following description and the accompanying 35 drawings in which similar characters of reference indicate similar parts throughout the several views.

In the accompanying drawings,

Fig. 1 is a sectional view of an embodiment of the invention.

Fig. 2 is a sectional view along the line 2—2 of Fig. 1.

Fig. 3 is a perspective view of a portion broken away of a modification of the invention.

Fig. 4 is a sectional view along the line 4—4 of Fig. 3.

Fig. 5 is a perspective view of a modified form of the spring and head element; and

Fig. 6 is a sectional view showing another modified form of the invention.

In carrying out our invention, we make use of a tubular pillar 1 terminating at its base in a conical portion 2, as shown in Fig.

55 1. This part corresponds to the neck and

upper base portion of the ordinary type of collar button. A mushroom head member 3 is provided and formed with an annular recess 4 for receiving the upper end of the pillar 1. The head 3 has a depending shank 60 5 which extends to a point in registration with the plane of the base of the collar button when fully restricted, as illustrated.

The lower end of the pillar has a reduced portion 6 which is projected through a central opening 7 in a steel band spring 8. This reduced portion is turned over by a riveting process, as shown at 9, to securely fix the spring to the shank.

The peripheral edges of the conical portion 2 are turned downwardly, as shown at 10, and extend for a distance slightly greater than the thickness of the spring 8.

A rear face plate 11 conforming in contour to the spring 8 presenting a convex 75 surface at the back, is provided to close the base portion 2 and its edges are turned over at 12 to firmly fix the plate to the base 2 of the pillar. It is obvious, therefore, that the spring 8 is capable of sliding between the 80 base part 2 and the plate 11 as the shank 5 is elevated or extended from the pillar 1.

We preferably set the spring 8, when it is tempered, so that it bears a greater degree of curvature than is shown in Fig. 1. Thus, 85 when the elements are in the position shown in the figure, there is yielding downward pressure exerted upon the shank and head by the spring to maintain the head in close engagement with the upper end 4 of the 90 pillar.

In operation, the collar button is inserted through the buttonholes of the collar band and collar in substantially the same manner as the ordinary type of collar button, but as 95 the head progresses through the buttonholes, it is extended away from the base against the action of the spring 8 so that when the head is passed through the last of the buttonholes, namely, one of the flaps of the collar, it will bear closely against the adjacent surface of the collar so as to compress all of the superimposed portions of the band and collar tightly together.

This condition consequently causes the 105 base portion 2 of the pillar to closely engage the adjacent surface of the collar band and thus bring the inner face plate of the button as closely as possible to the band and thus obviate the disadvantage of the pressure 110

of the plate against the neck of the wearer, as is usually the case in the ordinary type of collar button due to the absence of such means as we have provided for drawing the 5 head and base closely to the band and collar.

In Fig. 3, we have shown a modification of the structure illustrated in Figs. 1 and 2, which differs therefrom in the provision of a substantially rectangular pillar portion 1^a. 10 In this embodiment the shank is also rectangular in cross section, as shown in 5^a. The lower end of the shank has a slot 13 therethrough, through which the spring 8 is projected. In this form of the invention the 15 fillet 14, which corresponds to the conical portion 2 of the preferred form, has its greatest curvature on but two sides of the rectangular pillar 1^a. We have thus minimized the portion of the pillar occupied by 20 the spring 8 when the shank 5 and head 3 are extended.

In Fig. 5 is shown a still further modification of the invention. This form contemplates the use of a spiral tension spring 15 having a diameter equal to the diameter of 25 the peripheral portion of the conical base part 2. The spring 15 is closely clamped between the base portion 2 and the rear face plate 11, thus eliminating the provision of 30 the downwardly extending flange 10 used in the preferred form, and the spring is securely fixed against movement at its outer part. The inner end of the spring 16 is straight 35 and is arranged for disposition in a bore 17 extending transversely through the lower end of the shank 5. In all other respects this form is constructed and operates similarly to the first embodiment of the invention described.

40 In Fig. 6, we have shown a still further modification of the invention, in which means is provided for maintaining the head in an extended or protracted position. The essential parts consist of a head 3 with a 45 shank 5, and a pillar 1 having a convex base portion 2^a. Portion 2^a is rolled over at its peripheral edges 18 and clamps therebetween the peripheral edge 19 of a tempered disc 20. The interior portion of the disc 20 within 50 the bounds of the portion 19 is convex, as shown in Fig. 6, and normally yieldingly holds the head 3 and shank 5 in the position shown in the figure, the lower end of the shank being riveted at 9 to the disc 20 in the 55 same manner as employed for the spring 8.

When it is desired to extend the head 3 for the purpose of projecting the head through the buttonholes of the collar band and collar, the disc 20 is pressed inwardly so as to 60 snap past its center, i. e., the plane of the portion 19, and thus assume a position shown

in dotted lines. The head is thus held in extended position.

After the collar button has been properly inserted in the band and collar flaps, the 65 head is pressed inwardly to compress the collar and band portions and to cause the disc 20 to snap beyond its center and resume the position shown in Fig. 6.

Having thus described our invention, what 70 we claim as new and desire to secure by Letters Patent of the United States, is:

1. A collar button of the character described, comprising a base member including an upright tubular pillar, a head member formed with a longitudinally extending shank, said shank being slidably disposed in said tubular pillar, said head member being greater in diameter than the external diameter of said pillar whereby the inner face of the head may engage with garment portions surrounding said pillar, and a spring in said base member attached at its midpoint to said shank and having its ends slidably supported within the base member. 75 80 85

2. A collar button of the character described, comprising a base member including an upright tubular pillar portion, a head having a longitudinally extending shank, said head being recessed adjacent to and concentric with the butt of said shank to receive the upper portion of the tubular pillar when the head bears thereagainst, said head member being greater in diameter than the external diameter of said pillar whereby the 90 95 inner face of the head may engage with garment portions surrounding said pillar, and means for yieldably urging the head toward said base member. 100

3. A collar button of the character described comprising a hollow base member having an upright tubular pillar, a head member formed with a longitudinally extending shank, said shank being slidably disposed in said tubular pillar, said head being greater in diameter than the external diameter of said pillar and a flat band spring secured intermediate its length to the inner end of said shank and exerting tension on said shank tending to draw the head toward 110 the base portion, the opposite ends of said spring being slidably supported in said hollow base member and said base member being formed at its juncture with the pillar member so as to permit maximum flexing of 115 said band as in the projectile movement of the head. 105 110 115

In witness whereof, we hereunto subscribe our names this 18th day of January, 1927.

ROBERT A. NEILSON.
ARTHUR H. WATSON.
